HARDWARE FOR GUY STRAIN INSULATORS

Gregory C. Hill, Baltimore, Md., assignor to Locke
Insulator Corporation, Baltimore, Md., a cor-
poration of Maryland

Application April 1, 1931, Serial No. 527,000

3 Claims. (Cl. 173—366)

The invention relates to insulators, particularly those of the guy strain type and has for its general object the provision of novel hardware or means for connecting a plurality of insulators of this type in chain formation or to connect one with a stationary support, conductor clamp or the like.

The particular type of insulator dealt with in the carrying out of this invention is one of an elongated generally rectangular shape and formed as a dielectric body provided with transverse openings at right angles to each other, the material between the openings being placed under compression by the suspension or connecting hardware which passes through them. Ordinarily the faces of an insulator of this type are concaved. Furthermore the adjacent surfaces of the transverse openings are curved. In connecting insulators of this type or in connecting one with some supporting or other element a considerable problem arises as to avoiding undue strains which might damage the insulating material.

An important object of the present invention is to provide connecting hardware for an insulator of this type embodying separable parts which may be quickly and easily engaged with the insulator without requiring any bending or any peculiar manipulation to thread the parts through the transverse openings provided for their reception and to bring them into the proper position for connection with other elements.

Another object of the invention is to provide connecting hardware of this type embodying a member for engagement within the transverse opening, this member having a face or surface conforming in shape to the curvature of the inner wall of the opening so that the strains will be distributed throughout a relatively large area and be prevented from concentrating at any point.

Another object is to provide connecting hardware of this type including longitudinally extending members so shaped as to avoid contact with and the bringing of compressive strains upon the corners of the dielectric material so that there will be no risk of cracking, chipping or otherwise damaging the same.

An additional object is to provide connecting members of this character which will be simple and inexpensive to make, easy to apply, positive in action, efficient and durable in service, and a general improvement in the art.

To the attainment of the foregoing and other objects and advantages, the invention preferably consists in the details of construction and the arrangement and combination of parts to be here-

inafter more fully described and claimed, and illustrated in the accompanying drawing in which:

Figure 1 is a longitudinal section through a guy strain insulator constructed in accordance with my invention, one of the connecting links being in elevation and the other in section,

Figure 2 is a side elevation of what appears in Figure 1, and

Figure 3 is a cross section taken on the line 3—3 of Figure 1.

Referring more particularly to the drawing, the numeral 10 designates an insulator of the guy strain type formed as an elongated block-like body of dielectric material, usually porcelain, and having its longitudinal sides concaved as at 11, its longitudinal edges rounded off as at 12, and its corners rounded off as at 13. The body is formed with transverse openings 14 which are usually or preferably circular in cross section, at least at the center, with their ends flaring as shown. There are two of such openings arranged at right angles and having their adjacent or inner surfaces 15 curved, the convexity being toward the adjacent ends of the insulator. The openings 14 extend out into the centers of the concave faces 11.

In carrying out my invention I provide connecting means comprising links 16 and transverse members 17 connected therewith and extending through the openings 14. The links 16 are shown as formed from a single strip of metal of suitable gauge which may be a stamping, forging or casting and of angular shape to define portions 18 lying closely within the concave faces 11 of the insulator and to define converging portions 19 projecting beyond the end of the insulator and leading to spaced parallel attaching portions 20 apertured for the passage of a bolt 21, of course equipped with a nut 22, which is for the purpose of establishing connection of the links with similar links 23 carrying an adjacent insulator, or connection with a stationary support, conductor clamp or anything else desired. A lock nut washer 24 may be provided if desired. Preferably the portions 18 are concavo-convex in cross section or at least have their confronting faces convexed for conforming engagement within the concave faces 11. The free ends of the links 16 are preferably widened as at 25 and formed with rectangular openings 26 for a purpose to be described.

Each transverse member 17 is shown as comprising an elongated body which may conveniently be formed as a casting having one side

provided with a concave surface 27 conformingly engaging against the curved surface 15 of the opening 14 so as to distribute all strains throughout a large area. The ends of the member 17 extend through the openings 26 in the links 16 and are formed with horns or lateral projections 28 which overlie the outer ends of the openings 26 for preventing displacement. Transverse cotter 29 or the like may be inserted through suitable holes in the ends of the member 17 outwardly of the links for positively preventing any disconnection.

To assemble the hardware, the member 17 is threaded through the opening 14, which may be readily done by canting it, after which the links are manipulated to bring the openings 26 therein over the horns or projections 28. The links are then swung toward each other and engaged with the links 23 of the next adjacent insulator or with any other elements to which connection is to be made, and the bolt 21 is inserted and the nut 22 applied. The cotter 29 are then placed in position. The other member 17 is then placed through the other opening 14 and the other set of links 16 applied in the same manner.

In the use of hardware constructed in accordance with my invention it is apparent that there is no necessity for bending any of the parts to get them into place and in fact the parts are intended to be made sufficiently heavy that bending will not be possible as there is no desire to permit distortion of any sort after installation, the intention being that the construction be rigid so as to possess great durability and strength. Furthermore the parts are of such form that there will be no difficulty experienced in effecting insertion through the transverse openings in the insulator body. The provision of the horns on the transverse members is of great importance as these horns overlie the openings provided for their reception in the links and therefore positively prevent disconnection in service. By forming the transverse members with the concave faces they conformingly engage the inner walls of the transverse openings, thereby distributing the strains throughout a large area and avoiding concentration at any point or points. Actual service has demonstrated that with hardware constructed in this manner the porcelain is not subject to stresses and is protected against cracking, chipping or other detrimental actions.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. Connecting means for an insulator of the strain type formed as a body of dielectric material having transverse openings therethrough arranged at right angles to each other with the adjacent surfaces of the respective openings curved, comprising a single integral transverse member adapted to be inserted through each opening with its ends adapted to project beyond the opposite sides of the insulator, the transverse member having a curved face adapted to bear conformingly against the curved surface of the opening through

which it extends, a pair of links apertured at one end and engaged upon the projecting ends of each transverse member and adapted to lie along the sides of the insulator and having their other ends converging and terminating in attaching portions, each transverse member having its projecting ends formed with elongated integral lateral extensions projecting away from the converging ends of the links and overlying the links at the ends of the apertures therein.

2. Connecting means for an insulator of the strain type formed as a body of dielectric material having transverse openings therethrough arranged at right angles to each other with the adjacent surfaces of the respective openings curved, comprising a single integral transverse member adapted to be inserted through each opening with its ends adapted to project beyond the opposite sides of the insulator, the transverse member having a curved face adapted to bear conformingly against the curved surface of the opening through which it extends, a pair of links slotted at one end and engaged upon the projecting ends of each transverse member and adapted to lie along the sides of the insulator and having their other ends converging and terminating in attaching portions, each transverse member having its projecting ends formed with elongated integral lateral extensions overlying the links at the ends of the slots therein most remote from the converging ends of the links, and retaining elements extending transversely through the projecting ends of each transverse member outwardly of and overlying the outer faces of the links for maintaining the links closely against the body independently of the safety retaining function of said extension.

3. Suspension and connecting means for an insulator of the strain type formed as an elongated substantially rectangular body of dielectric material formed in its opposite faces with longitudinally extending grooves and formed with a pair of transverse openings arranged at right angles to each other and opening out into said grooves with the adjacent surfaces of the respective openings curved, comprising a single integral flat transverse metallic member insertable through each opening and having its ends adapted to project beyond the opposite sides of the insulator, a pair of links adapted to be disposed against the opposite sides of the insulator, said links being apertured at one end and engaged upon the projecting ends of each transverse member, said links being curved in cross section and of angular form and thereby adapted to conform to the curvature of the insulator at the grooves therein and thereby further adapted to be parallel with the sides of the insulator, the other ends of the links being adapted to project beyond the end of the insulator and converging and terminating in attaching means adapted to be connected with corresponding links adapted to be connected with an adjacent insulator, each transverse member being formed at its projecting ends with integral laterally extending horns located outwardly of and overlying the outer faces of the links connected with it and projecting entirely beyond that edge of the transverse member most remote from the converging ends of the links, the slots being of less length than said horns whereby the links must be canted with respect to the insulator to effect engagement upon said transverse member.

GREGORY C. HILL.
